UNITED STATES PATENT OFFICE.

ARTHUR C. BAUMANN, OF NEW YORK, N. Y.

EDUCATIONAL TOY.

Specification of Letters Patent. Patented Jan. 18, 1916.

1,168,274.

Application filed March 22, 1915. Serial No. 16,135.

To all whom it may concern:

Be it known that I, ARTHUR C. BAUMANN, a citizen of the United States, residing at New York city, in the county of New York, State of New York, have invented certain new and useful Improvements in Educational Toys; and I do hereby declare the following to be a full, clear, and exact description of the invention, such as will enable others skilled in the art to which it appertains to make and use the same.

This invention relates to new and useful improvements in toy apparatus, particularly that class wherein is provided a frame and a plurality of blocks movable in said frame to form words.

The object of the present invention resides in the provision of a toy apparatus provided with a plurality of members which may be moved around to form words.

A more specific object resides in the provision of such an apparatus wherein the word forming members may be arranged in the shape of a letter, including the usual superscription and so forth.

With the above and other objects and advantages in view, the invention resides more particularly in the novel combination formation and arrangement of parts more fully than emphasized, and pointed out in the appended claims.

Reference is had to the accompanying drawings, wherein similar characters of reference designate corresponding parts throughout the several views, and in which: Figure 1 is a plan view of the improved toy apparatus. Fig. 2 is a sectional view taken on the line 2-2 of Fig. 1. Fig. 3 is a detail sectional view on the line 3-3 of Fig. 1, and Fig. 4 is a perspective view of one of the letter blocks.

Referring now more particularly to the accompanying drawing, the improved toy apparatus comprises a rectangular base frame formed of the side and end bars 5 and 6 respectively. Arranged at the upper portion of the frame is a board or plate 7 corresponding to the superscription of a letter. This board is provided at one side with a longitudinal slot 8 directed at its inner end downwardly as at 9. The other side of the plate is provided with a parallel pair of slots 10, these slots communicating with a slot 11 disposed at right angles thereto, and extended to the inner edge of the plate. Disposed below the plate are a series of

strips 12, each having one end secured on the left hand side 5 of the frame, and terminating in spaced relation to the other side of the frame. Each of these strips are spaced a certain distance from each other, and the topmost strip is spaced from the plate 7. Secured at the top and bottom of the frame are a pair of strips 13, and secured on the left hand side of the frame between the strips 12 are a plurality of spacer blocks 14, these strips and blocks, together with suitable members 15 on the right hand side of the frame filling out the front of the apparatus so that it presents substantially a plane surface provided with channels formed by the various slots of the superscription plate 7, and the spaces between the strips 12. To provide a means for supporting and holding in place the otherwise free ends of the strips 12, blocks 16 are secured on the strips 13, and a bar 17 has its ends secured to this block, and extends over the ends of the strips, being spaced thereabove. Suitable bolt members 18 are passed through the strips, and engaged in the ends of the strips. Thus such strips are held in a manner which will not interfere with the letter-blocks 19, which are slidably held in these channels. The central portion of the bar 17 is strengthened by a brace 20 secured thereto and to a block 21 on the frame. Each of the letter blocks 19 is of substantially cylindrical shape and of greater diameter than the width of the channels. Each block is provided with an annular groove 22, adapted to receive the side edges of the strips 12 or the sides of the plate 7 adjacent the channels therein whereby the letter-blocks are slidably held in the channels. The bottoms of the letter-blocks are preferably tapered at 23, and the top of each block has burned or otherwise inscribed thereon a letter or other symbol 24.

It is observed that by the provision of the holding bolts 18 of the blocks may pass freely at the right hand end of the strip 12. To provide a means for holding the blocks against displacement at the ends of the strips, and at the same time to facilitate the passage of said blocks from one strip to another or to plate 7, a strip 25 is secured to the members 15, and is substantially the width of the annular groove 22, the distance between the ends of the strips 12 and said strip 25 being substantially the width of the said channels. Thus, in operation, the

blocks may be freely moved about in the various channels and from one to another so that a child may with this apparatus compose a letter with the conventional form of superscription. There has thus been provided a comparatively simple and durable toy apparatus which is highly interesting and which is at the same time instructive.

What is claimed is:

- 10 1. A toy apparatus comprising a frame a plurality of strips secured to one side of the frame, and terminating short of the other side, said strips being spaced to form channels, letter-blocks slidably held in said channels, and adapted to pass between the ends of the strips and the frame, and means for securing the otherwise free ends of the strips.
- 20 2. A toy apparatus comprising a frame, a plate secured at the upper end of the frame, a plurality of spaced strips secured to one side of the frame, and terminating short of

Copies of this patent may be obtained for five cents each, by addressing the "Commissioner of Patents, Washington, D. C."

In testimony whereof, I affix my signature, in the presence of two witnesses.

ARTHUR C. BAUMANN.

3
said other side, said plate being provided with slots opening at the inner edge thereof, said slots, and the spaces between the strips, and between the free ends of the strips and the adjacent side forming channels and letter-blocks slidably held in said channels.

3. In a toy apparatus, a rectangular frame, spaced strips each secured at one end to one side of the frame, and having its other end spaced from the other side of the frame, blocks on the ends of the frame, a bar secured to said blocks, and disposed over the free ends of the strips and spaced therefrom, and bolts passed through said bar and the ends of the strips.
